CLAIM

The ornamental design for a hoe head, substantially as shown.

DESCRIPTION

FIG. 1 is a right side elevational view of a first embodiment of the hoe head showing my new design, the left side being substantially identical thereto.

FIG. 2 is a front elevational view thereof.

FIG. 3 is a rear elevational view thereof.

FIG. 4 is a top plan view thereof.

FIG. 5 is a bottom plan view thereof.

FIG. 6 is a partial auxiliary view of a portion thereof as taken on line VI—VI of FIG. 1 to better show the true shape of a portion thereof.

FIG. 7 is a perspective view of the first embodiment as seen from above and somewhat to one side.

FIG. 1
